Harry Berman, Bronx, Vito Errico, New Hyde Park, and Dominick Lofrese, Bronx, N. Y.

Application February 20, 1952, Serial No. 18,608

Term of patent 7 years

(Cl. D57—1)

To all whom it may concern:

Be it known that Harry Berman, Vito Errico, and Dominick Lofrese, each a citizen of the United States of America, residing at Bronx, county of Bronx, and State of New York; New Hyde Park, county of Nassau, and State of New York; and Bronx, county of Bronx, and State of New York, respectively, have invented a new, original, and ornamental Design for a Spectacle Front, of which the following is a specification, reference being had to the accompanying drawing, forming part thereof.

The essential features of our design for a spectacle front reside in the parts shown in full lines.

We claim:

The ornamental design for a spectacle front, substantially as shown and described.

HARRY BERMAN.

VITO ERRICO.

DOMINICK LOFRESE.
